UNITED STATES PATENT OFFICE.

EARL C. STAFFORD, OF PHILADELPHIA, PENNSYLVANIA, ASSIGNOR TO THE UNITED STATES TRAIN SIGNAL COMPANY, OF PORTLAND, MAINE, A CORPORATION OF MAINE.

TRAIN-SIGNAL SYSTEM.

Application filed March 7, 1921. Serial No. 450,195.

My said invention relates to certain improvements over the train signal system shown in application No. 380,286 of Benn and Davies, filed May 10, 1920, and it is an object of the same to provide means whereby the system may be used with equal facility in a train composed wholly of cars equipped with the electro-pneumatic signaling device shown in my prior application No. 380,151, filed May 10, 1920, or in a train comprising cars so equipped and others not so equipped.

Referring to the accompanying drawings which are made a part hereof and on which similar reference characters indicate similar parts,

Figure 1 shows a diagrammatic view of an electric circuit for a train unit such as a passenger car or the like together with the cooperating instrumentalities for giving a signal or transmitting the same to another portion of the train.

Figure 2 is a similar view of the signaling instrumentalities for a train unit such as a locomotive,

Figure 3 is a plan of my air relay, and Figure 4 a vertical section thereof.

In the drawings reference character 5 represents a signaling device such as is shown in my prior application above referred to comprising preferably both visual and audible instrumentalities. A pipe 6 is connected to the air brake train pipe and to an audible device on the signaling means 5 such as a whistle or "sisser" so that the compressed air from the pipe will operate the signal when the circuit is broken.

Reference numeral 7 indicates a section of a conventional air signal train pipe. A branch 8 connects the train signal pipe to an air relay or fluid pressure circuit controller 9, the details of which are fully explained in my co-pending application of even date herewith Serial No. 450,196. The section of air brake train pipe to which pipe 6 is connected and the section 7 of the train signal pipe are coupled together by means of pipe couplings such as are shown in application No. 380,286 above referred to, or in any other desirable manner.

The circuit comprises a conductor 10 with a battery 11 connected between sections of the same and a conductor 12 comprising sections co-acting with a circuit controller 13,

the signaling device 5 and a second circuit controller 14. At the ends of the car are switches 15 and 16 by means of which the circuit may be closed at the proper end of the front or the rear unit of the train. The long and short devices shown at 17 and 18 represent the long and short jaws of an air brake hose coupling as in co-pending application No. 380,286 and it will be evident that train units carrying a system such as shown may be connected end to end in series regardless of which end is foremost.

The circuit controller 14 is or may be as disclosed in co-pending application No. 380,286 of Benn and Davies, filed May 10, 1920, being manually controlled by the usual conductor's cord or a cord running parallel thereto attached to the rings 19 and running to the opposite ends of the particular car or other unit so that the controller may be operated from any part of the car or other train unit on which the same is located.

To the system of the prior application I have added a circuit controller 13 comprising a fluid-pressure circuit-controller attached to the air signal train pipe containing air under pressure. This device is shown in detail in Figures 4 and 5 and comprises base members 25 and 26, forming therebetween a cavity in which is a diaphragm 27. A plate 28 rests on the diaphragm and prevents the same from being blown through an aperture in an extension 29 on base member 26. The base member 25 has a threaded opening to which pipe 8 is connected for applying compressed air to the diaphragm. The diaphragm is normally held down by a spring 30 in the extension, a screw 31 having threaded connection with the extension forming means for adjusting the tension of the spring. A rod 32 extends through the nut and engages at its upper end an insulating block 33 set in a lever 34 pivoted at 35 to a support 36.

The support 36 is fastened to extension 29 by screws 37 and is insulated from the block by a plate 38 and collars 39 about the screws, said plate and collars being formed of any suitable insulating material. The lever 34 carries a movable contact member 40 and is normally held in the position shown by a spring 41 attached by screws or the like to the lever and the base member 26. Contact

40 is adapted to engage stationary contact 41 mounted in a support 42 attached to extension 29 by screws 37 in the same manner as support 36. The contact 41 forms a part of a screw 43 by means of which it may be adjusted toward and away from contact 40. A nut 44 on screw 43 constitutes means for locking the same in adjusted position. A block 45 fastened to base member 26 by screws or other means forms a support for a pair of binding posts 46 connected to supports 36 and 42 by wires 47 and screws 48, the binding posts being connected to conductor 12. The signaling devices use so little air they do not effect any reduction in normal train pipe pressure, the slight loss being more than balanced by the leakage through leak valves provided in the passages from the reservoirs. Whenever the pressure in the signal train pipe is reduced the circuit is broken at 13 and a signal is operated on each unit of the train including both cars and locomotives, this being true, however, only if all train units are equipped with electro-pneumatic signalling devices, or otherwise only of those equipped units that are connected in a circuit.

Preferably I so arrange the devices as to be very sensitive, so that a very slight change of pressure is sufficient to break the circuits and cause operation of the signaling devices. As explained in my co-pending application I arrange the signaling devices so as to require a minimum of power in the circuit for operating the same.

I have also modified the equipment of the locomotive shown in application No. 380,286 by adding thereto a battery 11, a circuit controller 13, with its controlling means attached to the train signal pipe 7 and a valve 20 of any conventional form in the branch 8' with a conductor's cord 21 for operating the same to lower the pressure in the pipe. In my present arrangement it is immaterial whether the locomotive is connected to an equipped car or an unequipped one so long as there is an air pipe on the car and an unequipped car may also be connected anywhere in the train of cars without interfering with the operation of the signaling means on the equipped cars. Signal cords extending from front to rear of the cab, or from front to rear of the engine, if desired, extend forward and back from rings 19 on circuit-controller 14 of the engine.

It is evident that operation of the circuit controllers 14 will not serve to transmit a signal past an unequipped car as a circuit is not closed through such a car. If now a member of a train crew on an equipped unit should desire to transmit a signal past an unequipped unit to the engineer and he attempted to operate the controller 14 the signal, of course, will not be transmitted. Securing no response after one or two attempts

he will naturally use the other operating means, i. e. a cord connected to the ordinary conductor's valve.

If the entire train is equipped with the electro-pneumatic signaling device the engineer will use the circuit controller 14 only and so will the entire train crew since in such a case the compressed air signal pipe becomes a mere superfluity. As in the prior application the system will be operated by parting of the train, grounding of a wire, or breaking of the circuit due to any other contingency, as well as by manual means, the semaphore going to the danger position and staying there while its audible signal sounds continuously. The entire device is then operated as in the modification described in application No. 380,286. It will frequently happen, however, that one or more cars not equipped with electro-pneumatic signaling devices will constitute part of the train and in such case, provided they have an air signal pipe, the signaling will be done by the train crew by pulling a cord to operate the conductor's valve of the usual type now found in trains for signaling the engineer and the engineer may signal back to the crew by pulling the cord 21 to operate valve 20. Any decrease of air pressure in the pipe will of course break the circuit in every car and on the locomotive and thus give both visible and audible signals on all cars connected in a circuit with the engine or with each other.

It may be found desirable where a train is thus made up of equipped and unequipped units to divide the engine circuit adjacent the air relay and to provide a switch at 22 in one branch of the divided circuit in addition to the switch 13 in the other. The electro-pneumatic system may then be used alone if all the train units are equipped with my electro-pneumatic signalling devices. The signal pipe sections in this case need not be coupled up, as the pipe is not used at all. It may also be desirable, as shown in Figure 2 to connect a switch 14' to the engineer's cord for the engine valve whereby both will be operated whenever either is actuated by the engineer. This expedient is contemplated for use only where unequipped cars are liable to be used as a portion of a train.

It will be obvious that I may also omit the circuit controller on the engine and if this be done the engineer can signal to the crew by the cord operated reduction valve and signal pipe, and the crew may signal to the engineer by the conductor's valve and signal pipe in similar fashion; if one of the train crew should pull the cord attached to controller 14 on a car he will get no response from the engineer and will thereby perceive his error as the electric circuit is not completed throughout the train. It will be understood that the usual pressure is kept up in the signal train pipe by conventional

means such as a connection to the main reservoir on the engine.

It is within the contemplation of my invention to utilize the train equipment now in ordinary use, merely removing the whistle fixture from the engine and substituting therefor the air relay device shown in my application, No. 450,196. The electro-pneumatic signaling instrument and a battery are also placed on the engine and the relay operated with ordinary straight air pressure from the train signal pipe. By thus substituting the air relay and signal for the whistle I enable the engineer to signal back to the train crew as well as the train crew to signal to the engineer in the usual manner, the only difference being that a signal in the cab is operated instead of the engine whistle.

I may also attach the pipe 6 to the signal pipe instead of the brake pipe if desired. In such case operation of circuit controller 14 would lower the pressure in signal pipe 7 and this would cause the air relay or relays to operate and open the circuit at each switch 13.

Other modifications of my system will occur to those skilled in the art of signaling and therefore I do not limit myself to the precise form thereof shown in the drawings and described in the specification, the true scope of the invention being set forth in the appended claims.

Having thus fully described my said invention, what I claim as new and desire to secure by Letters Patent, is:

1. In a train signaling system, a plurality of signaling devices mounted on different units of the train comprising an audible signaling means connected to the train air brake pipe, means on each train unit whereby a closed electric circuit may operate on such unit or between a plurality of units and means connected to the air signal train pipe for breaking said circuit to cause operation of the signaling device, substantially as set forth.

2. In a train signaling system, a plurality of signaling devices mounted on different units of the train comprising an audible signaling means connected to the train air brake pipe, a normally-closed electric circuit extending through the train and means on each train unit connected to an air line of the train for breaking said circuit to cause operation of the signaling device, substantially as set forth.

3. In a train signaling system, the combination of a plurality of signaling devices mounted on individual train units, an electric circuit adapted to connect a plurality of equipped train units, manually operated circuit controllers for breaking the circuit to transmit a signal from one unit to another in either direction of the length of the train,

and means whereby the signaling device on the engine may be operated from other train units if an unequipped train unit is interposed between the equipped units of the train, substantially as set forth.

4. A train signaling system comprising a signal on a locomotive, a train pipe connected thereto for operating the signal by variations of air pressure, means including an electric circuit normally preventing operation of the signal said circuit being divided for a part of its course, a manually operated switch in one branch of the circuit, a fluid-pressure-controlled switch in the other branch, a second train air pipe connected thereto, a normally closed circuit controller in the main line of the electric circuit, a valve in the second train air pipe and means for simultaneously opening said valve and actuating said circuit closer to break the circuit, substantially as set forth.

5. A train signaling system comprising a signal on a locomotive, a train pipe connected thereto for operating the signal by variations of air pressure, means including an electric circuit normally preventing operation of the signal, said circuit being divided for a part of its course, a manually operated switch in one branch of the circuit, a fluid-pressure-controlled switch in the other branch, a second train pipe connected thereto, a valve in the second train pipe, and a cord connected to said valve for operating it, substantially as set forth.

6. In a signaling system for trains, electrically operated signals, a train signal pipe, a normally closed electric circuit on the train, means for operating the signals when the circuit is broken, and means including a fluid pressure operated switch connected to the signal pipe adapted to break the circuit on reduction of pressure in said pipe, substantially as set forth.

7. A train signaling system comprising a pneumatic signal on each of a succession of train units, common pneumatic means for operating all of said signals including a train pipe connected to each signal, means including a circuit common to all of said units controlling all of said signaling devices and including alternative branch circuits on one unit, a switch in each branch, a second train pipe, means including a fluid pressure switch connecting the train pipe to one of each pair of circuits, and a circuit controller in said circuit on each train unit operable by a conductor's cord, substantially as set forth.

In witness whereof, I have hereunto set my hand at Washington, District of Columbia, this 19th day of February, A. D. nineteen hundred and twenty-one.

EARL C. STAFFORD.
